[57] CLAIM

The ornamental design for a fountain pen for artists and calligraphers or the like, as shown and described.

DESCRIPTION

FIG. 1 is a right front perspective view of a fountain pen for artists and calligraphers or the like showing my new design;

FIG. 2 is a right side elevational view, the left side being a mirror image thereof;

FIG. 3 is a front elevational view thereof;

FIG. 4 is a rear elevational view thereof; and

FIG. 5 is an exploded perspective view with the cap removed to expose the conventional nib assembly.

FIG. 2

FIG. 4

FIG. 3
